DART GAME BOARD

Ruhl H. Reed, 3006 Ridgeway Drive,
Fort Wayne, Ind. 46816

Filed Apr. 21, 1975, Ser. No. 570,018

Term of patent 14 years

Int. Cl. D21—07

U.S. Cl. D34—5 PP

The figure is a front view of a dart game board showing my new design.

The side opposite that represented in the figure, and the outer peripheral edge of conventional thickness is plain.

I claim:

The ornamental design for a dart game board, substantially as shown and described.
